UNITED STATES PATENT OFFICE

141,050

DESIGN FOR A MOLDING FOR STORE FRONTS

Morris Ketchum, Jr., New York, N. Y., assignor to The Kawneer Company, Niles, Mich., a corporation of Michigan

Application August 4, 1944, Serial No. 114,738

Term of patent 14 years

(Cl. D13—6)

To all whom it may concern:

Be it known that I, Morris Ketchum, Jr., a citizen of the United States, residing at New York, in the Borough of Manhattan and State of New York, have invented a new, original, and ornamental Design for Molding for Store Fronts, of which the following is a specification, reference being had to the accompanying drawing, forming a part thereof.

In the drawing the figure is a perspective view of a molding for store fronts showing my new design.

I claim:

The ornamental design for a molding for store fronts, substantially as shown.

MORRIS KETCHUM, JR.
